DINNER PLATE OR SIMILAR ARTICLE

Pascal L'Anglais, New York, N. Y., assignor to
Onondaga Pottery Company, Syracuse, N. Y.,
a corporation of New York

Application May 19, 1951, Serial No. 15,247

Term of patent 14 years

(Cl. D44—15)

To all whom it may concern:

Be it known that I, Pascal L'Anglais, a citizen of the United States, residing at New York city, State of New York, have invented a new, original, and ornamental Design for a Dinner Plate or Similar Article, of which the following is a specification, reference being had to the accompanying drawing, forming part hereof.

The sole figure is a plan view of a plate of conventional configuration, showing my new design. The dominant feature of the design resides in the central ornamentation shown on the plate.

I claim:

The ornamental design for a dinner plate or similar article, as shown and described.

PASCAL L'ANGLAIS.
